UNITED STATES PATENT OFFICE.

JOSEPH A. WILKIN, OF MATAMORAS, PENNSYLVANIA.

TURNSTILE.

Application filed May 28, 1922. Serial No. 563,024.

To all whom it may concern:

Be it known that I, JOSEPH A. WILKIN, a citizen of the United States, and resident of the town of Matamoras, county of Pike, 5 State of Pennsylvania, have invented certain new and useful Improvements in Turnstiles, of which the following is the specification.

The device, the subject of this invention is 10 a turn stile, particularly adapted for use at amusement parks, railway stations or elsewhere where passenger or passage traffic is to be collected and has for its particular objects the construction of a turn stile that 15 will be positive in its operation and yet particularly silent as the continuous use of a noisy turn stile is exceedingly irritating.

Another object of the invention is to produce a turn stile so constructed that continuous operation is practically assured, the parts being so formed as to withstand continued and excessive wear. I have, however, so constructed my turn stile that if wear does occur, the worn parts or the parts 25 subject to wear may be readily removed and replaced and while my turn stile may operate with a coin controlled electrical releasing means, I will show and describe such means only briefly as they are not intended to form an important part of this 30 invention.

In the specification which follows, the details of construction and other objects will be fully set forth and the accompanying 35 drawings should be referred to for a complete understanding of the specification which follows:—

In the drawings:—

Fig. 1, is a plan view, the casing being 40 fractured to show the enclosed mechanism.

Fig. 2, is a sectional view through the casing and track, the other mechanisms being shown in elevation.

Fig. 3, is a perspective view of the turn 45 stile element.

Fig. 4, an enlarged sectional view, at about mid-center the controlling mechanism.

Fig. 5, is an enlarged sectional view 50 through the controlling roller and its support.

Similar reference numerals indicate like parts in all the figures where they appear.

The turn stile consists of a cross shaped member having arms 6, 7, 8, and 9 and between which the passenger or operator will 55 step to operate the turn stile.

The arms 6 to 9 inclusive are supported upon a standard or column 10 and as the arms should be formed of wood, I will provide supporting plates 11 and 12 upon the 60 standard 10, one at each side of the arms and between each the arms are received and secured by bolts or rivets 13.

The standard may be continuous throughout its entire length, the lower end should, 65 however, be reduced as shown at 14 to be received into the bearing block 15 and to overcome undue friction, the lower end of the standard 10 may be tapered to produce a cone bearing 16.

The controlling mechanism for the turn stile is received in the casing, preferably formed in two parts 17 and 18, secured together by bolts 19 and in securing these parts together, I include and retain by the 70 bolts 19, a track guide member 20.

Upon the standard 10 and within the casing, I arrange a collar 21, securing thereto a pair of guide rails as shown at 22 and 23 and spaced therefrom, I arrange another 80 pair of guide rails 24 and 25. In each pair of guide rails, I arrange T-shaped guides 26 and 27 secured together by a bolt 28 and upon this bolt and between the guides 26 and 27 is a grooved pulley 29. It will be noted that at the opposite side of the standard 10, another pair of guides 30 and a grooved pulley 31 are arranged and that these guides and their supported pulleys are urged outward by springs 32 and 33.

The springs 32 and 33 arranged parallel, are received in cup members 34, 35, 36, and 37, which cup members are secured to bars 38 and 39, the bars having projections 40 and 41, which bear against the innermost 90 edges of the guide members 26, 27, and 30 respectively.

The lower guide rails 24 and 25 may be secured to a collar 42 and adjacent this collar, I arrange a plate 43 having a plurality 100 of indents 44, into which the core 45 of a solenoid 46 may be inserted. This core member 45 has a spring pressed latch and may be cut at an angle in one direction, so that operating with the angular indents 44 105 in the plate 43, the turn stile may operate freely in one direction, but may operate in the other direction only when the core member 45 is electrically withdrawn.

One of the most important parts of my 110 device is the track member 20 upon which the rollers 29 and 31 operate. This member

is shown in plan in Fig. 1 and its operation will be understood. The rollers as shown in Fig. 1 are in the "stop" position.

When the turn stile is advanced until the 5 roller 31 reaches the point 47 and the opposite roller reaches the point 48 and passes just beyond that point, the operation of the 10 springs 32 and 33 will cause the turn stile to continue in movement until the rollers 15 meet the depressions 49 and 50, at which time the motion of the turn stile will be arrested until the next application of pressure causes the rollers to advance beyond the projection 51 and the projection directly 20 opposite, whereupon the rollers will move 25 into the position shown.

While modifications may be made within the scope of the appended claims, I prefer the whole as shown and described; it will, 20 however, be understood that the rollers 29 and 31, the guide bars 22 to 25 inclusive and the track member 20 may be formed of wood if preferred, the other parts, with the exception of the arms 6 to 9 should be of 25 metal.

Having carefully and fully described my invention what I claim and desire to obtain is as follows:—

1. A turn stile having a casing, an irregular

track secured to said casing, a standard 30 operable through said casing, rollers supported by and movable with said standard and in engagement with said track and means for urging said rollers toward said track, said means comprising springs, one 35 arranged at each side of said standard.

2. A turn stile comprising a standard and an irregular track in fixed relation, guide bars secured to said standard and extending at each side thereof, carriages operable in 40 said guide bars, one said carriage being arranged at each side of said standard, a roller in each said carriage and operable upon said track and a plurality of springs 45 between said carriages for urging said rollers toward said track.

3. In a turn stile, a means for controlling the operation thereof, said means comprising two sets of parallel guide bars, carriages between pairs of bars, rollers upon said 50 guides and means for urging said rollers and guides outward and a track having a plurality of depressions of different depths, into which said rollers are free to pass to control the movement of said turn stile.

Signed at the city, county and State of New York, this 19th day of May, 1922.

JOSEPH A. WILKIN.
